FOIL CONTAINER

Samuel M. Weisberg, Edward H. Paulsen, and Henry Silbermann, Baltimore, Md., assignors, by mesne assignments, to National Dairy Research Laboratories, Inc., New York, N. Y., a corporation of Delaware

Application April 2, 1946, Serial No. 658,999

2 Claims. (Cl. 229—37)

1

This invention relates to improvements in containers, and it relates particularly to improved containers formed of metallic foil and to the blanks from which such containers are formed.

Thin flexible metal has been widely used in small collapsible and disposable containers for pasty and liquid materials. However, metallic foil has not been satisfactory for larger disposable containers such as cartons for milk, other liquids, ice cream, and semi-liquids or pasty materials, for the reason that it lacks the necessary rigidity to withstand shock and maintain its shape under the weight of the liquid or other material therein.

The larger disposable containers have been made heretofore of treated cardboard of sufficient thickness to support the weight of the material therein. Such containers are not very attractive and are not entirely sanitary. The waterproof coating usually consists of a wax mixture which melts at sterilizing temperatures, thereby rendering sterilization difficult. This coating is sufficiently soft to permit dust and dirt to adhere to it, even at ordinary room temperature and lower.

A demand exists for more attractive and more sanitary containers such as would be provided by containers made from metal foils, such as aluminum foil, aluminum alloy foils and the like if they could be made sufficiently sturdy for the purposes desired. Such containers could be sterilized readily, would not present surfaces to which dust or dirt adheres strongly and, moreover, would present bright attractive surfaces to which advertising and decorative material could be applied readily.

An object of the present invention, therefore, is to provide containers formed of metallic foil which are sufficiently strong to permit their use for packaging milk, other dairy products, beverages, semi-liquids and pasty materials, as well as solids in commercially suitable quantities.

Another object of the present invention is to provide metallic foil containers that are reinforced suitably to impart increased rigidity to the containers.

A further object of the present invention is to provide containers formed of metallic foil which are reinforced with metal foil integral with the remainder of the container.

An additional object of the invention is to provide blanks from which reinforced metal foil containers can be formed.

Other objects of the invention will become apparent from the following description of typi-

2

cal forms of the invention selected to illustrate the invention.

In accordance with the present invention, we have provided containers which are made up wholly of a metallic foil, such as for example, an aluminum foil or an aluminum alloy foil of such thinness that it normally is incapable of withstanding shock and impact to which it might be subjected under normal usage. The container is formed preferably of a continuous blank having panels therein forming the sides and end closures of the container and having connecting webs between the side panels which may be folded over in order to form reinforcements at or adjacent to the corners of the container. Such folded webs may take the form of overfolds of substantially flat nature or rolled overfolds forming beads at the corners of the containers.

The containers may be further strengthened by providing similar overfolds in the side panels so that the side panels are reinforced lengthwise and rendered more rigid.

It is also possible to provide the side panels with suitable decorative and reinforcing corrugations of X, diamond form or other form as may be desired and the containers may be supplied with suitable decorative or advertising material.

Containers embodying the present invention are characterized by substantially greater rigidity and resistance to impact and compression and are able to withstand the weight of a liquid or semi-liquid or pasty material therein without distortion.

The containers being formed of metal, may be sterilized without danger of leakage and having a smooth, polished surface, do not retain dust or dirt.

For a better understanding of the present invention, reference may be had to the accompanying drawings in which:

Figure 1 is a plan view of a typical form of blank for producing a container having square ends and rectangular side walls;

Figure 2 is a perspective view of a container produced from a blank like that disclosed in Figure 1;

Figure 3 is an end view of the container disclosed in Figure 2 showing one of the overfold beads partially shaped;

Figure 4 is an enlarged sectional view taken through one corner of the container disclosed in Figure 3;

Figure 5 is an end view of a modified type of container having a flat overfold at its corners,

one of the overfolds being illustrated in partially completed form;

Figure 6 is an end view of a further modification of the container showing overfolds at the corners of the container overlapping adjacent side walls and illustrating one of the overfolds in partially completed condition;

Figure 7 is a plan view of a modified form of container blank providing webs between portions or sections of the side panels of the container to be formed into overfolds extending longitudinally of the panels and at the corners of the container;

Figure 8 is a perspective view of one type of the container formed from a blank of the type disclosed in Figure 7;

Figure 9 is a perspective view of another type of container that can be formed from a blank like that disclosed in Figure 7; and

Figure 10 is an end view of the container disclosed in Figure 9.

The forms of containers and blanks from which such containers are produced are illustrated herein as having square ends and rectangular side panels. It will be understood that the ends of the containers may be of triangular, rectangular, pentagonal or other polygonal shape and three or more side panels may be provided. Also, the containers may be cylindrical, conical, frusto-conical, pyramidal, or frusto-pyramidal. The forms of the invention described hereinafter, therefore, should be considered as illustrative of the invention.

The containers disclosed in Figures 2 to 6 inclusive may be produced from a sheet of metallic foil, such as aluminum or aluminum alloy foil generally of the shape illustrated in Figure 1. This blank includes a plurality of rectangular side panels 10, 11, 12 and 13 which form the sides of the completed container C, as illustrated in Figure 2. The panels 11 and 13 are provided with end flaps 14 and 15 and 16 and 17, respectively, which are of the proper shape to form the ends of the container C and, as illustrated, may be square.

The side panels 10 and 12 are provided, respectively, with the shorter flaps 18, 19, 20, and 21 which are adapted to be folded to complete the ends of the container in the usual way.

Interposed between the side panels 10 and 11, 11 and 12, and 12 and 13, respectively, are integral webs 22, 23, and 24, respectively, which when properly folded, form reinforcements for the container as will be described presently.

The panel 10 is also provided with a laterally projecting tab 25 which includes a web 26 and a flap portion 27 which is adapted to be secured to the panel 13 with the web 26 between the panels 10 and 13 to complete the container.

The flap 27 and the end flaps 14 to 21 inclusive may be secured together in any suitable way, for example, by means of a suitable heat-setting adhesive and the edges of the flaps 14, 15, 16, and 17 may be sealed to the adjacent ends of the panels 10, 11, 12, and 13 by means of flexible cellulose or foil tapes having adhesive thereon, by crimping or beading the edges, or in any of the other known ways, for providing a liquid-tight joint. If desired, additional overlapping flaps 14a, 14b, and 14c and flaps 15a, 15b, and 15c, may be provided for sealing the ends of the containers as shown in dotted lines in Figure 1.

One group of end flaps, for example, the flaps 14 and 16 may be provided with apertures, not shown, which overlie each other and permit the

contents of the container to be emptied therefrom.

Containers formed of foil which are generally of the shape illustrated in Figure 2 have insufficient strength when formed of aluminum or aluminum alloy foils. For example, containers formed of aluminum foil of a thickness of .0035 of an inch collapse easily under pressure and will not maintain their shape under ordinary conditions of handling.

In order to improve the strength and rigidity of the containers, the webs 22, 23, 24, and 25 have been added to the blanks, these webs being suitably shaped and arranged to provide integral overfolds or reinforcements at the corners of the containers.

Referring now to Figures 2, 3, and 4, the overfolds may be formed by folding the webs 22, 23, 24, and 25 along their axial center lines, as illustrated in Figure 3, to provide a flap of double thickness projecting outwardly from the adjacent edges of the side panels 11 and 12. This folded web, for example web 23, may be rolled, as illustrated in Figure 4, to form a coiled bead at the corner of the container which extends the entire length of the corner and greatly stiffens and reinforces the corner.

The webs may be treated in a different manner in order to reinforce the corners of the container and the container as a whole, as illustrated in Figure 5. In this form of the container, the webs 22a, 23a, 24a, and 25a may be folded along their center lines and then pressed flat against the sides 10a, 11a, 12a, and 13a of the container to form reinforcing overfolds extending longitudinally of the container adjacent to its corners.

Figure 6 illustrates a further modification of the overfold. Thus, the webs 22b, 23b, 24b, and 25b of the container may be folded along spaced apart parallel lines extending lengthwise of the webs and the webs then are pressed into engagement with the panels on opposite sides of the webs to overlap these panels and form reinforcing overfolds extending along the corners of the container.

Tests have shown that containers having reinforced corners, such as those described above, have two to three times the strength, under compression, of a container lacking such overfolds. The strength of containers having the rolled overfolds at the corners, as shown in Figures 3 to 4, is the greatest, whereas the other types are less strong. Also, the resistance to impact of containers of the type described above is far in excess of the resistance to impact of containers which lack the reinforcements at the corners. Thus, a container with no reinforcement when subjected to impact was mashed and holes were produced in the container, whereas containers having overfolds at the corners were only slightly deformed and no breaks were produced in the foil under the same impact.

The strength of the containers can be increased further by providing overfolds extending lengthwise of the side panels of the container. A typical form of blank for producing such a container and containers produced from such blanks are illustrated in Figures 7 to 10 inclusive. As disclosed in Figure 7, the container made up of a plurality of side panel portions 30, 31, 32, 33, 34, 35, 36, and 37 each having suitable flaps on their ends for forming the ends of the container. Interposed between the various side panels 30 to 38 inclusive are integral webs 39, 40, 41, 42, 43, 44, 45, and 46 which are adapted to be formed into

overfold reinforcements. In preparing a container, such as the container 50 disclosed in Figure 8, the webs 39 to 46 may be folded in the manner described in connection with Figure 5 of the drawings to bring the side panels 30 and 31, the side panels 32 and 33, the side panels 34 and 35, and the side panels 36 and 38, respectively, into edge to edge engagement to form the four sides of the containers with overfolds at the corners and in the middle of the sides.

As shown in Figure 8, the folded webs 39 to 46 may be pressed flatly against the adjacent panels to form longitudinally extending reinforcements.

Alternatively, the webs 39 to 46 may be folded, as illustrated in Figure 6 of the drawings, to cause them to overlap the panel portions adjacent to each of the webs. This construction is disclosed more clearly in Figure 10 of the drawings.

The overfolds may be further modified if desired to make them of bead or rod-like formation, as disclosed in Figures 3 and 4, to increase the strength of the container.

The same type of overfold reinforcement may be applied with equal facility to a cylindrical or other type of container by providing suitable connecting webs that may be folded or otherwise formed into reinforcements around the circumference of the container. Also, the side panels of the container can be stamped or otherwise provided with corrugations of any desired design or shape to strengthen the container and improve its ornamental appearance.

It will be understood, therefore, that the invention is susceptible to considerable modification and should not be limited save by the appended claims.

We claim:

1. A container comprising a hollow body of polygonal cross-section having closed upper and lower ends and side panels of greater height than width, the edges of greater length being adjacent

15

and angularly related to form corners extending from the lower end to the upper end, said body being formed of thin metallic foil having little resistance to impact and buckling stresses, said corners having a reinforcement of foil of substantially uniform dimensions integral with said side panels adjacent thereto and extending the full length of said corners, said reinforcement comprising a substantially cylindrical rolled bead having at least six layers in diametric cross section.

2. A container comprising a hollow body of polygonal cross-section having closed upper and lower ends and side panels converging toward each other to form corners extending from the lower end to the upper end, said body being formed of thin metallic foil having little resistance to impact and buckling stresses, said corners having a reinforcement of foil integral with said side panels adjacent thereto and extending the full length of said corners, said reinforcement comprising a substantially cylindrical rolled bead having at least six layers of foil therein in diametric cross section.
